UNITED STATES PATENT OFFICE.

ROBERT H. KNIGHT, OF IUKA, ILLINOIS.

TOOL-DRIVER.

1,242,205.

Specification of Letters Patent.

Patented Oct. 9, 1917.

Application filed December 4, 1916. Serial No. 134,883.

To all whom it may concern:

Be it known that I, ROBERT H. KNIGHT, a citizen of the United States, residing at Iuka, in the county of Marion and State of Illinois, have invented certain new and useful Improvements in Tool-Drivers, of which the following is a specification.

This invention relates to new and useful improvements in means for driving rotary tools such as bits, stump drivers and the like.

Referring to the drawings;

Figure 1 is a side elevation view of the machine;

Fig. 2 is a transverse sectional view taken 15 on the line 2—2 of Fig. 1;

Fig. 3 is a partial vertical sectional view; and

Fig. 4 is a transverse sectional view of the ratchet mechanism.

Referring more particularly to the drawings, the reference character 1 represents a yoke, in one end of which is mounted a shaft 2 having a pressure head 3 thereon.

Rotatably mounted in the opposite end of 25 the yoke 1 is a shaft 4 the upper end of which is enlarged as at 5 and provided with a circular series of depressions or the like 6.

The end of the shaft 4 is slotted as at 5, and received within said slot is a projection 30 8 carried by the free end of a spiral member 9, the other end 10 of which is rotatably mounted in a recess 11 in the end of the shaft 2.

Mounted around the enlarged head 5 of 35 the shaft 4 is a collar 12 in which are mounted at opposite sides, pivoted pawls 13 and 14 and suitably secured to said collar 12 is a resilient member 15 which is adapted to engage the pawls to secure the same in engagement with the openings 6 in the enlarged head 5 of the shaft 4.

Pivottally mounted as at 16 in the yoke by 45 means of a bolt 17 is a lever 18, one end of which is bifurcated as at 19 and engages the spiral member 9 to rotate the same upon rocking movement of the lever 18.

From the foregoing it will be seen that as the lever 18 is rocked on its pivot 17, the spiral member 9 will be rotated due to this

engagement with the bifurcated end of said lever, and by shifting the member 15 circumferentially of the collar 12 the pawls 13 or 14 may be engaged with the notches 6 to determine the direction in which the shaft 4 is driven.

55

Claims:

1. A device of the character described comprising a yoke, a shaft mounted in each end of the yoke, a spiral member mounted in the shafts, means for rotating the spiral member, and means for connecting one of the shafts with the spiral member to rotate said shaft.

2. A device of the character described comprising a yoke, a shaft mounted in each end of the yoke, a spiral member mounted between the shafts, means for connecting the spiral member with one of the shafts, and means pivotally mounted in the yoke and engaging said spiral member to rotate the same and drive the shaft when connected thereto.

3. A device of the character described comprising a yoke member, a shaft mounted in each end of the yoke member, a spiral member mounted between the shafts, means for connecting the spiral member to one of the shafts to rotate the same, and a pivoted lever mounted in the yoke and adapted to rotate the spiral member to rotate the shafts.

4. A device of the character described comprising a yoke member, a shaft mounted in each end of the yoke member, a spiral member mounted between the shafts, means for operatively connecting the spiral member to one of the shafts, and a bifurcated lever pivotally mounted in the yoke at right angles to the spiral member and having its furcations embracing the same to rotate the spiral member upon rocking movement of the bifurcated lever.

In testimony whereof I affix my signature in the presence of two witnesses.

ROBERT H. KNIGHT.

Witnesses:

GEO. E. KNIERIM,
H. L. LOGAN.
